SELF-PRIMING PUMP

Alfred S. Marlow, Jr., Ridgewood, N. J.

Application November 3, 1949, Serial No. 125,302

2 Claims. (Cl. 103—113)

1

The present invention relates to improvements in liquid pumps, and in particular to pumps classified by their mode of construction and operation as diffuser centrifugal pumps.

Characteristic of centrifugal pumps is the requirement for priming. This is generally considered to be the inherent weakness of a standard centrifugal pump, although to some degree known centrifugal pumps are constructed to perform a partial priming function, either by a system of recirculation priming or by diffuser priming, in which case the pump is considered to be a self-priming centrifugal pump. In recirculation priming, a connection is made between the suction side of the pump and a pump reservoir on the discharge side providing a passage for recirculating priming liquid. Thus, when air enters the suction side of the pump, depriving it of its normal operating prime, a suitable by-pass control valve is actuated either manually or automatically to provide recirculation within the pump or the system so that pumping action may be sustained. Diffuser priming, on the other hand, is distinguished from recirculation priming by reason of the fact that the priming fluid from the pump reservoir does not return all the way to the suction side of the pump, but rather returns only to the circumferential portion of the impeller where it is admixed with air and ejected through diffuser passageways. As this action continues, all air is eventually removed and the pumping function returns to normal.

There are important advantages in the use of the diffuser principle of priming as compared with recirculation priming, particularly in that auxiliary valve mechanisms are not necessary which, in recirculation priming pumps, are subject to mechanical failure. Once set in operation and given an initial prime, the diffuser type centrifugal pump will continue to operate when entrained air or gas is admitted to the pump on the suction side. The diffuser priming centrifugal pump, in fact, requires no more moving parts than are required with a standard non-priming centrifugal pump.

Requisite conditions for fluid flow to give efficient discharge and those for effective diffuser priming are directly opposite. Diffuser priming effectiveness is promoted by the existence of conditions which result in a large degree of turbulence at the impeller which, of course, are intolerable conditions for efficient discharge. With turbulence of the priming liquid, greater quantities of air or gas may be entrained with the priming liquid and transported to discharge or

2

to a ventilating separator in series with the pump. At the same time, however, balance must be preserved whereby the diffuser construction does not create undue friction losses during pumping.

It is the principal object of the present invention to provide a diffuser priming centrifugal pump having a novel and efficient diffuser for both priming and pumping.

10 A further object of my invention is to provide a diffuser type centrifugal pump capable of day-in and day-out pumping service in an efficient manner.

15 A further object of my invention is to provide a diffuser type centrifugal pump wherein the diffuser element is of novel design, arranged to increase priming turbulence at the circumference of the impeller and yet to retain a relatively non-turbulent flow during pumping.

20 These and other objects and advantages of my invention, which will be understood during a consideration of the following detailed description of a preferred physical embodiment, are attained, in part, with a closed diffuser associated with a

25 closed centrifugal impeller, the diffuser passages being so constructed that alternate passages are of the same size and shape while adjacent passages are of dissimilar size and shape. Likewise, the separation distance of the diffuser element

30 at the entrance to the diffuser passage from the periphery of the impeller for alternate diffuser passages are alike while for adjacent diffuser passages the separation distance is dissimilar. Thus, a maximum amount of turbulence results and, at the same time, the volute construction of the passages is maintained so that friction loss will be small consistent with the necessary transposition from velocity to pressure in the fluid.

35 The invention will best be understood by consideration of the detailed specification which follows, taken in conjunction with the drawings in which,

40 Figure 1 is a vertical cross-section view of a diffuser centrifugal pump employing the principles of my invention, and

45 Figure 2 is a cross-sectional view through the pump of Figure 1 taken along lines 2—2.

Referring to the drawings, the centrifugal pump of my invention may include a pump casting or housing 10 which encloses an impeller 11 fixed to the end of a pump shaft 12 extending through the packing lantern 13 and trunnioned in the outside bearing bracket 14, the lantern 13 forming an hermetically sealed closure member 50 against the side of housing 10. Intake for the

pump is taken at the suction entrance 15 on the left hand side, the flow of fluid being directed thence past the suction check valve 16 to the closed entrance of a diffuser element 17, through which it is directed via aperture 18 to the central portion of impeller 11.

Centrifugal force, which is derived as the impeller rotates by contact of the fluid against the impeller vanes 19, tends to throw the liquid outwardly from the impeller through the diffuser passages 20 and the priming holes 20', the latter of which are arranged somewhat according to the A. C. Stratton Patent 2,281,175. Diffuser passages 20 are generally constructed in volute form to transform the flow from high velocity at low pressure to lower velocity and higher pressure, consistent with the requirements for which the pump is built, and to maintain low friction losses.

At exit from the diffuser passages 20 and from priming holes 20', the liquid flows through the pump casing 10 and into the discharge outlet 21, thence past the check valve 22 into the discharge line 23. It will be noted that, in the instance of the pump illustrated, casing 10 is sufficiently large to form a substantial reservoir for a supply of priming fluid, although it is to be understood that any other suitable reservoir may be used which, for example, may be entirely separate from the pumping housing. Further possibilities include the supplementary use of a float operated ventilating air separator in series with the pump in accordance with the devices of my co-pending application, Serial Number 10,752, filed February 25, 1948, which avoid the pumping of air or gas into a closed system.

Referring to Figure 2, vanes 19 on impeller 11 of the present pump are curved backward with respect to the direction of impeller rotation indicated by the arrow, to receive the fluid from the suction entrance without shock and to avoid undesirable eddying during its transposition from the center to the periphery of the impeller. The diffuser passages 20 are in part defined by the vanes 24 which lie substantially tangent to the peripheral portion of the impeller and radiate therefrom with forward volute curvature. At the same time, the side walls of passages 20 are tapered, as shown in Figure 1, and thus the diffuser serves to slow down the velocity of the fluid during pumping with a minimum of friction and eddying.

Of importance, alternate diffuser passages 20 are of the same size and shape while adjacent passages are of dissimilar size and shape. As shown in Figure 2, there are an even total number of passages, every alternate passage being a smaller passage and, likewise, every alternate passage is approximately twice the size of the smaller passages. I have found this two-to-one ratio to be desirable as a general rule although variations may of course be resorted to depending upon the proportions of the pump, the quality of liquid, and the speed of operation. It will also be noted that alternate vanes 24 have the same slight operating clearance with respect to the periphery of the impeller, while adjacent vanes have dissimilar clearance, resulting in inter-communication between adjacent diffuser passages, the purpose of which will be herein-after understood.

Priming or port holes 20' are arranged approximately midway of the diffuser passages 20 and enter from the passage into the reserve liquid space within casing 10, in accordance with the

aforementioned patent to A. C. Stratton Number 2,281,175 issued April 28, 1942 for Priming Means for Self-Priming Pumps. As illustrated, port holes 20' are disposed only in the larger diffuser passages serving to enhance the priming action, but they may also be provided in the smaller diffuser passages if conditions warrant. Further, the ports may be doubled or otherwise used in multiple depending upon the priming effect desired and upon the shape, size, and disposition of the diffuser passages and the vanes.

In operation, assuming that the suction line is airbound and that a supply of liquid exists in the pump reservoir, the reserve or priming fluid will tend to flow toward the impeller in the diffuser passages until it strikes the rotating impeller to be thrown outwardly. I conceive that, since the optimum conditions for fluid flow from the impeller dictate the adoption of volute curves for the diffuser vanes, counter-flow toward the impeller from the passages defined by volute shaped vanes will result in the greatest degree of disturbance at the impeller to assist priming. At the same time, this disturbing effect is multiplied by establishing interference from one passage to the next adjacent passage which I produce by the application of dissimilar passage widths and prescribed intercommunication between passages at the impeller periphery. As priming of the pump progresses, a more uniform condition of flow replaces the turbulence of the first stages of priming in the diffuser and flow becomes bi-directional with a fluid and air admixture moving outwardly while a more dense priming fluid moves inwardly. By proportioning the size of the alternate passageways, the location of priming holes, and the separation of alternate diffuser vanes for a particular pump and for a particular set of pumping conditions, this bi-directional flow may be effectively regulated to arrive at the most desirable priming cycle. Inherently, the volume characteristics of inflow and outflow in priming will differ, and while a two to one ratio has been referred to, the size of the alternate passages may be modified if desired for improved overall priming effectiveness. Further priming will then rid the pump entirely of air and the pump will again reach a stage of continuous outflow from all of the diffuser passages. Thus, during pumping, the conditions for fluid flow remain substantially according to good engineering principles while during priming the added splashing and eddying at the impeller periphery results in an increased tendency to pick up and pump air from the suction side of the pump and carry it to discharge.

As hereinbefore noted, I have chosen a ratio of two-to-one for the widths of adjacent passages while it is contemplated that other ratios may prove equally or more efficient for some pumping conditions. I further consider that it may be desirable to produce repetitive groups of three or more inter-communicating diffuser passage patterns around the periphery of the impeller in pumps of large size, the important consideration being to build up the air or gas accumulating effect by the leverage influence of the conditions at adjacent diffuser passages.

While I have illustrated the centrifugal pump incorporating the features of my invention to include a closed impeller and closed diffuser, it is understood that other styles of construction may be utilized and that various modifications and

refinements may be resorted to, and that no limitations are intended other than as defined in the subjoined claims.

Having thus described my invention I claim:

1. In a self-priming fluid pump, in combination, a pump housing including a reservoir for a supply of reserve fluid, a suction inlet and a discharge outlet in the pump housing, a centrifugal impeller arranged for axial rotation within the housing to exert driving forces for advancing liquid from the suction inlet through the reservoir to the discharge outlet, said impeller having its center of rotation in communication with said suction inlet, and a diffuser fixed intermediate of the periphery of the impeller and the reserve fluid reservoir and containing a series of co-extensively radiating flow passages separated from each other by the use of curved vanes, alternate vanes being equally spaced from the periphery of the impeller but consecutive vanes being unequally spaced from the periphery of the impeller, and alternate passages being provided with ports for direct communication from the impeller to the pump reservoir.

2. In a self-priming fluid pump, in combination, a pump housing including a reservoir for a supply of reserve fluid, a suction inlet and a discharge outlet in the pump housing, a centrifugal impeller arranged for axial rotation
